CENTRIFUGALLY FORMED BALE OF FIBROUS MATERIAL AND THE LIKE

Lloyd B. Smith, 607 N. 31st St., Birmingham, Ala.
Original application Dec. 4, 1962, Ser. No. 242,215.
Divided and this application Nov. 18, 1963, Ser. No. 324,318

3 Claims. (Cl. 206—83.5)

This application is a division of my co-pending application Serial No. 242,215, filed December 4, 1962, "Process and Apparatus for Centrifugally Baling Fibrous Materials and the Like and Bale Formed Thereby."

This invention relates to bales of fibrous materials such as cotton, synthetic fibers and the like.

In my prior co-pending applications, Serial No. 33,301, filed June 1, 1960, "Process and Apparatus for Baling Fibers and Bale Formed Thereby," now Patent No. 3,133,563, and Serial No. 69,649, filed November 16, 1960, "Construction for High Gravity Centrifuges and the Like," now abandoned, I show, describe and claim a process and apparatus for baling fibers and an improved form of construction for high gravity centrifuges useful for this purpose.

In the centrifugal baling of materials such as lint cotton to obtain densities on the order of 20 pounds per cubic foot, I have encountered, under certain conditions, a problem of maintaining the apparatus in balance. Thus, when baling such fibers and employing the concepts of the present invention, the centrifuge has a tendency toward dynamic unbalance. I have discovered that in such cases the layers of fibers as they are laid on in forming the bale are put in such tension that the layers actually shear, part or cleave, thus throwing more weight on one part of the centrifuge wall than on the others, causing unbalance. When it is understood that the cylinder portion of the centrifuge in question may be on the order of 52 inches in diameter by 20 inches long and that it may be rotated at around 1800 r.p.m., the seriousness of even a small unbalance will be appreciated.

In attempting to solve this problem, I have conceived, and in actual practice have proven, that one solution is purposefully to cause the layers of fibers to cleave or break at diametrically opposite points as the bale is formed. In this way there is no sudden breaking or cleaving of the layers and hence no sudden, unbalancing shifting of the weight. Starting with the very first or outermost fibers delivered to the centrifuge, therefore, I purpose to form that layer and subsequent layers into at least two circumferential extending parts, thus in effect stress relieving by such cleavage what otherwise would eventually become layers of highly tensioned bands which eventually upon the piling on of other layers would part at some random line, shifting circumferentially, and causing unbalance.

Briefly, my invention contemplates a bale of fibers and like materials formed in a centrifuge in which the bale is purposefully caused to cleave or part commencing at predetermined, generally diametrically opposed points, along generally radially opposed lines, whereby the unbalancing conditions referred to are never permitted to materialize.

My invention contemplates a centrifugally formed bale in which when the outer wrapper or container is removed, the bale parts along the cleavage lines already mentioned, thus facilitating the opening of the bale for use of the fibers therein in textile or other processes.

Apparatus illustrating constructional features of a centrifuge which may be used for forming my improved bale is shown in the accompanying drawings, forming a part of this application, in which:

FIG. 1 is a somewhat diagrammatic view of a centrifuge

2

equipped with my improved cleavage inducing members;

FIG. 2 is a sectional view taken generally along line 2—2 of FIG. 1 and showing the centrifuge with the bale therein completed, prior to removing the same from the centrifuge;

FIG. 3 is an enlarged detail sectional view showing one method of attaching the cleavage inducing members to the interior of the centrifuge; and

FIG. 4 is an isometric view of one of the cleavage inducing members.

Referring now to the drawings for a better understanding of my invention I illustrate somewhat in diagrammatic manner a centrifuge C. The apparatus may be supported on a shaft 10 mounted in a bearing 11 and power for rotating the apparatus may be supplied through a pulley or the like indicated diagrammatically at 12 from a source of power 12a.

The centrifuge proper may embody the outer shell portion 13 and the radial portion 14. In actual practice it will be understood that the shell and radial portions are made separately and preferably are connected together by the pin construction shown, described and claimed in my aforesaid patent application Serial No. 69,649. However, for the purposes of illustrating the present invention, I have shown a somewhat conventional centrifuge in order to eliminate details from the drawings and description. A removable door 16 is provided and the door has an opening 17 therethrough. The door may be held in place by means of centrifugal latch pins 18.

It will further be understood that the fiber to be baled will be placed in a kraftboard or other container. This container may embody three parts, namely, the circumferential or cylindrical shell portion 19, a rear circular head 21 and a front circular head 22. The head 22 has an opening 23 therein corresponding to the opening in the door. Fiber to be baled is delivered in an airborne stream through a conduit 24 the end of which may be moved into the centrifuge and, with the centrifuge rotating the air is expelled either out of the openings 17 and 23 or is drawn out, partly, by means of a special nozzle which forms the subject of another of my co-pending applications Serial No. 286,016, "Process and Apparatus for Packaging or Baling Fibrous Materials and the Like," filed June 6, 1963. As shown diagrammatically, the feed tube or conduit 24 may be reciprocated from the inner dotted position indicated to a position just inside the door opening by means of a double acting fluid pressure cylinder 25. At 25a is a movable baffle which serves to turn the fiber stream toward the periphery of the centrifuge. Suffice it to say that the fiber is delivered, either in an airborne stream or otherwise, into the centrifuge while it is rotating and is directed toward the inner periphery thereof, thus to form the bale.

Extending axially of the centrifuge, substantially for the full effective length thereof are the cleavage inducing members 26. As shown in the drawings I provide four of these members, preferably, although in some instances two of them will suffice. It will be noted that they are spaced equally, that is, 90° apart or, if only two are used, 180° apart.

The members 26 may be mounted in any convenient manner inside the centrifuge. Further, they might even be mounted inside of the circumferential portion 19 of the container. Preferably, I mount the members 26 by means of studs 27 which pass through slightly enlarged openings 28 in the radial portion 14 of the centrifuge so that the members are slightly loosely mounted at one end only. The object of this is to permit ready insertion of the circumferential package part 19. In order to accommodate the rear circular part 21 of the package I provide triangular openings 29 in the package disc 21 so that this member,

when readying the machine for operation, simply is slipped into the machine around the members 26 and lies against the inner wall of the radial part 14.

As shown particularly in FIG. 4, the members 26 may be in the form of generally triangular shaped pieces as viewed in cross section, there being a drilled and tapped hole 31 in the rear ends of the members to receive the studs 27.

From what has been described it is now possible to explain more fully the operation of the apparatus to produce my improved bale.

It will be understood that as the fiber enters the machine the centrifugal force causes the same to accumulate in uniform layers on the inner surface of the circumferential packages part 19. If the centrifuge is rotating, say, in the neighborhood of 1800 revolutions per minute, it will further be apparent that there may be no well defined "layers" as such, since the rate of delivery of the fibers compared to the speed of the surface on which they are deposited will prevent any formation of true, distinct layers in the sense of there being visible divisions, cross-section-wise, between the fibers. However, without the members 26 it will be seen that the introduction of the fiber builds up a band of fiber, at any given instant, which is under terrific tensile pull. It is the shearing or pulling apart of these stressed bands which has heretofore caused the trouble in these centrifuges. With the members 26 in place, as the fibers are delivered into the machine to form the entire bale B, the members 26 induce the formation of actually, in the case shown, four separate sections of the bale as viewed in cross section. That is, from the very beginning the layers are formed with the definite spiral, generally radially extending cleavage lines 32 indicated in FIG. 2 defining the sections. Therefore, at no time is there any tendency for the fiber to shift in any manner, thus maintaining the centrifuge in balance.

In actual practice upon removing either of the end discs of the package from bales made by my invention the lines indicated at 32 are quite distinctly visible. Upon opening the bale by cutting the circumferential part 19 (which incidentally may contain metal bands either embedded in the kraftboard or on the outside thereof, not shown), the bale actually falls apart into four separate segments, dividing itself along the lines 32, for the entire length of the bale. In practice, with a 500-pound bale of cotton at a density of approximately 23 pounds per cubic foot, no imbalance was noted in the formation of such bale and upon opening such bales they actually do fall apart precisely as indicated.

I attribute the successful functioning of my invention to the fact that instead of permitting the bale to shear or cleave at random, I purposefully stress relieve such tendency by actually forming the bale from the very beginning with the break or part lines 32, due to the provision of the members 26 or equivalent means. I have baled dozens of bales of different materials such as Orlon, nylon, cotton, and the like, in a machine of the size herein indicated and in each instance have eliminated all dynamic balance problems and have provided bales which come apart into sections, thus facilitating further processing of the fibers into the opening room of a textile mill. It will be understood that with the apparatus shown the feed tube 24 actually enters the openings 17 and 23 to deliver fibers to the centrifuge and then when the machine is stopped the hole in the center closes up as indicated

in FIG. 2. Hence, the lines 32 do not necessarily come all the way to the geometric center of the bale inasmuch as the cleaving action mentioned stops short thereof.

From the foregoing it will be apparent that I have invented an improved bale of fibers. In actual experimental practice my invention has proven to be extremely satisfactory. When utilized with the pin construction shown in my above application Serial No. 69,649, and with the features of the invention described in my application Serial No. 33,301, I have provided a centrifugal baling apparatus which is entirely practical and in which gravities heretofore unheard of in machines of this size are obtainable in the ordinary course of their operation. It will be seen that the bale formed by my invention is divided along the spiral radial lines into sectors of substantially equal mass. It will be understood that any reasonable number of the cleaving inducing members may be used, for instance four of them. At all events whatever number is used they are spaced equi-angularly around the inside of the centrifuge.

Within the meaning of this disclosure the spiral radial lines of cleavage are contemplated by and included in the expression "generally radial lines" and similar expressions.

While I have disclosed in this application the baling of "fibrous materials" it may well be that there are other materials which would lend themselves to baling by my improved process and apparatus. However, my experiments to date do not permit me at this time to state precisely what other materials than cotton, Orlon, nylon and the like can be successfully baled. Therefore, within the meaning of this disclosure and the appended claims, the term "fibrous material" is intended to include all materials which in fact are capable of being baled by the use of my invention.

While I have shown my invention in but one form, it will be obvious to those skilled in the art that it is not so limited but is susceptible of various changes and modifications without departing from the spirit thereof, and I desire, therefore, that only such limitations shall be placed thereupon as are specifically set forth in the appended claims.

What I claim is:

1. A bale of fibrous material generally cylindrical in shape and divided longitudinally into at least two segments along lines of cleavage extending from the periphery of the bale toward the center thereof.

2. A bale of fibrous material generally cylindrical in overall configuration divided longitudinally into at least two generally equal segments along oppositely disposed generally radially extending spiral lines.

3. A bale of fibrous material in the shape of a cylinder having a diameter greater than its length, said bale being divided into a plurality of substantially equal segments along lines of cleavage extending from the periphery thereof toward the center of the bale.
